Primary Examiner — Cynthia Underwood*(74) Attorney, Agent, or Firm* — Sheridan Ross P.C.**CLAIM**

The ornamental design for a protective cover for an electronic device, as shown and described.

DESCRIPTION

FIG. 1 is a front elevation view of the protective cover for an electronic device;

FIG. 2 is a right elevation view thereof;

FIG. 3 is a left elevation view thereof;

FIG. 4 is a bottom plan view thereof;

FIG. 5 is a top plan view thereof; and,

FIG. 6 is a rear elevation view thereof.

The broken lines showing portions of the protective cover for an electronic device are provided for illustration purposes only and form no part of the claimed design.
